UNITED STATES PATENT OFFICE.

MILTON D. MESEROLE, OF MILFORD, CONNECTICUT, ASSIGNOR TO HAYES & MESEROLE
MFG. CO., OF MILFORD, CONNECTICUT, A FIRM.

HAIR CURLER.

Application filed June 5, 1922. Serial No. 566,064.

To all whom it may concern:

Be it known that I, MILTON D. MESEROLE, a citizen of the United States, residing at Milford, in the county of New Haven and State of Connecticut, have invented a new and useful Improvement in Hair Curlers; and I do hereby declare the following, when taken in connection with the accompanying drawings and the characters of reference marked thereon, to be a full, clear, and exact description of the same, and which said drawings constitute part of this application, and represent, in—

Fig. 1 a plan view of a hair curler constructed in accordance with my invention.

Fig. 2 a side view of the same.

Fig. 3 a longitudinal sectional view thereof.

Fig. 4 a plan view of the tip end of the
tongue.

Fig. 5 a side view of the same.

Fig. 6 a sectional view on the line 6—6 of Fig. 1.

Fig. 7 an end view, showing the ends of the
frame welded together.

Fig. 8 a sectional view, illustrating the guard formed with a stoplip. This invention relates to improvement in

This invention relates to improvement in hair curlers, particularly those formed from wire, and is an improvement on the construction shown in Patent No. 1,416,301. These hair curlers comprise a frame formed from wire, with a tongue hinged to one end of the frame and with a slide on the frame to engage with the outer end of the tongue. When in use, the tongue and frame are bowed longitudinally, owing to the mass of hair between them, and in some cases, the tongue will slip out from the guard. One object of this invention is to provide means for interlocking the tongue with the guard.

In my previous patent, the sides of the frame were flattened to form stops to limit the movement of the guard. This required a

45 separate operation and another object of this invention is to provide stops by bending the frame, and the invention consists in the construction as hereinafter described and particularly recited in the claims.

50 In carrying out my invention, as in my previous patent, I preferably form the frame from a strip of wire, the central portion of which forms a rear bar 10, from which sides

11 and 12 project, the ends 13 and 14 being turned inward to meet and form a longitudinal frame. Preferably, the ends 13 and 14 will be entered into a sleeve 15, which forms a stop for the purpose hereinafter described. In each of the sides, near their outer ends, I form outward bends 16 and 17. The tongue is preferably formed from a single piece of wire doubled at the center to form a tip 18, the ends of the tongue being formed with eyes 19 and 20, which are bent around the bar 10. In my previous patent, the tip of the tongue was flattened, but instead of flattening the tip of the tongue, I prefer to strike the metal inward from both sides to form notches 21 and 22. Folded around the side bars, beyond the bends 16 and 17, is a slide 23, formed from a strip of metal folded into box shape and adapted to be moved back and forth on the sides 11 and 12, its movement, however, being arrested in the inward direction by the bends 16 and 17 and in the outward direction by the sleeve 15. It is obvious, however, that this slide may be formed with a centrally-arranged lip 24, as in my previous patent, or the ends 13 and 14 of the wire may be soldered or welded together and upset to form projections 25 and 26, as shown in Fig. 7 of the drawings, these projections forming a stop to limit the outward movement of the guard. The device is used in the usual way, that is, hair is folded around the one member and the other member pressed down over it, and the guard moved rearward over the tip of the tongue. As the tongue is bowed longitudinally when in use, the edge 27 of the guard will be engaged by the notches in the tip of the tongue, these notches being sufficient to so engage with the edge of the guard as to become interlocked therewith, so that the tongue is not liable to spring out from the frame or to force the tongue forward, out of engagement with the tip.

I claim:

1. A hair curler, comprising a frame, a tongue hinged thereto, and a guard sliding on said frame, said frame formed on opposite sides with outwardly-extending bends forming stops for the inward movement of the guard. 100

2. A hair curler, comprising a frame, a guard sliding on said frame, and a tongue

hinged to the frame and formed at its tip with notches adapted to engage with the edge of the guard.

3. A hair curler, comprising a frame formed from a single piece of wire bent to provide a rear bar and two sides, the ends of the wire turned inward, a tongue hinged to said rear bar, said tongue formed near its tip with notches, and a slide mounted on 10 said side bars of the frame and adapted to

extend over the tip of the tongue, the inner edge of the guard being engaged by the notches in the said tongue.

In testimony whereof, I have signed this specification in the presence of two subscribing witnesses.

MILTON D. MESEROLE.
